UNITED STATES PATENT OFFICE.

CHARLES E. LORD, OF MILWAUKEE, WISCONSIN.

SYSTEM OF CONTROL.

1,046,473.

Specification of Letters Patent. Patented Dec. 10, 1912.

Application filed November 30, 1910. Serial No. 594,820.

To all whom it may concern:

Be it known that I, CHARLES E. LORD, a citizen of the United States, residing at Milwaukee, in the county of Milwaukee and State of Wisconsin, have invented certain new and useful Improvements in Systems of Control, of which the following is a full, clear, and exact specification.

This invention relates to systems of control of the separately actuated contact type in which the several controller contacts or switches are arranged to be operated successively and automatically.

The object of my invention is to so construct and arrange the controller contacts and their connections as to prevent a too rapid successive operation of the contacts thereby preventing a too rapid acceleration of the motor controlled thereby.

In carrying out my invention I obtain the proper time element between successively operated switches by means of a compressible resistance device, preferably an automatically operated compressible carbon resistance element.

The various novel features of my invention will be described in the specification and particularly set forth in the appended claims.

The invention is illustrated somewhat diagrammatically in the accompanying drawing.

The motor 10, here shown as having a shunt field 11, is connected to a source of supply 12 by a switch 13. In order to vary the speed of the motor, sections r' , r^2 , and r^3 of resistance are connected in series with said motor. These sections of resistance are adapted to be cut into and out of the motor circuit by automatically operated electromagnetic switches 1, 2, and 3, the operations of which are controlled by solenoids 14, 15, and 16 respectively included in the energizing circuit or circuits 17. The energization of the solenoids 14, 15, and 16 is controlled by time element devices 18, 19, and 20. Each of these devices, considering the first device 18 particularly, includes a variable compressible resistance member 21 preferably formed of a pile of carbon disks. The time element devices are adapted to be actuated by magnets 22, the energizing coils 23 of which are in the motor circuit.

To prevent a too rapid successive operation of the switches 1, 2, and 3 by a sudden and sharp heavy compressive action of the

devices 18, 19, and 20, said devices are provided with retarding members or dash-pots 24. The pressure on the variable compressible resistance mediums is thereby applied gradually, decreasing the effective resistance of said medium, and permitting a current of increasing value to flow. The circuits including the variable resistance mediums and the coils of the magnets which control the variation of the effective resistance of said variable resistance mediums are in parallel, and the energizing coils 14, 15, and 16 respectively of the switches 1, 2, and 3 are connected in series with their corresponding variable resistance members.

When the line switch 13 is closed current is forced through conductor 25, bridging contact 26 of switch 3, conductor 27 to point 28. Here the current divides, part passing through energizing coil 23, sections r' , r^2 , and r^3 of resistance, and motor 10 to ground G. The motor 10 is thereupon set in rotation and gradually increases its speed a predetermined amount. The other part of the current passes through variable resistance member 21, energizing coil 14 of switch No. 1, and conductor 29 to ground G'. The current passing through the variable compressible resistance member 21 is small due to the fact that the resistance of said carbon pile or resistance member is comparatively high when it is not compressed. But as the magnet 22 gradually effects the compression of the variable resistance medium 21 the current passing therethrough increases in value until it reaches a certain predetermined strength which enables the coil 14 to actuate and close switch No. 1, cutting section r' of resistance out of the motor circuit and permitting the motor to take on an increment of speed. At this time the motor current passes from the source of supply through conductor 25, bridging contact 26, conductor 27, coil 23 of device 18, bridging contact 30 of switch No. 1, actuating coil 23 of device 19, sections r^2 and r^3 of resistance, through motor 10 to ground G. The energizing circuit includes the same path as above mentioned until the point 31 is reached where it divides and passes through the second variable resistance medium 32 of device 19, solenoid 15, conductor 29 to ground G'. As the operating magnet 22 of device 19 gradually effects the compression of the carbon pile 32, current will pass through the solenoid 15, increasing in value

until it reaches a certain predetermined value, at which value it operates and closes switch No. 2, cutting out the second section r^2 of resistance and permitting the motor 10 to take on another increment of speed. The motor current will now take a path through conductor 25, bridging contact 26, conductor 27, coil 23 of device 18, bridging contact 30, coil 23 of device 19, bridging contact 34 of switch No. 2, coil 23 of device 20, section r^2 of resistance, motor 10 to ground G. The current used for actuating the switches 1, 2, and 3 will take exactly the same path to the point 35 where it will divide, passing through carbon pile 36 of device 20, solenoid 16, conductor 29, to ground G'. As the carbon pile 36 is gradually compressed, the strength of the current passing therethrough will increase proportionately until it has reached a certain predetermined value when it will energize the solenoid 16 sufficiently to operate the switch No. 3, bringing its bridging contact 37 into engagement with its corresponding stationary contacts 38, 39, and 40, and breaking the connection between its bridging contact 26 and its stationary contacts 41 and 42. At this point the third and last section r^2 of resistance is cut out of the motor circuit which now includes only the switch 13, conductor 25, conductor 43, bridging contact 37, motor 10 to ground G. Switch No. 3 is retained in this position by a holding coil 44 which receives its current through conductors 25 and 43, bridging contact 37, passing through a resistance 45, conductor 29 to ground G'. The resistance 45 is inserted in the circuit for the purpose of cutting down the energizing current while the motor is in continuous operation. When switch No. 3 is operated and retained in this running position it breaks certain circuit connections including energizing magnets 22, solenoids 14, 15, and 16, thereby causing the switches No. 1 and No. 2 to open. But switch No. 3 is held in its closed or running position by the holding coil 44. When the line switch 13 is opened, current will cease to pass through the holding coil 44 and switch No. 3 will be returned to its original starting position and the separately actuated contact motor controller would again be in its initial position preparatory to starting the motor again.

It is evident that there may be various modifications in the arrangement here shown and described, and I intend in my claims to cover all such modifications which do not involve a departure from the spirit and scope of my invention.

What I claim as new is:

1. An automatic circuit controller comprising a plurality of switches, and time limit means controlling said switches, said means comprising an element the resistance

of which varies with change of pressure and a solenoid in parallel with said element controlling the change in pressure.

2. An automatic circuit controller comprising a plurality of electromagnetic switches, and time limit means controlling said switches and comprising an element or elements the resistance of which varies with change of pressure and means in parallel with said element or elements controlling the change in pressure. 70

3. An automatic circuit-controller comprising a plurality of switches, operating magnets for said switches, and compressible resistance means in circuit therewith for controlling the operation of said magnets. 80

4. An automatic circuit controller comprising a plurality of switches, operating means therefor, and compressible resistance means in circuit with said operating means for controlling the operation of said operating means. 85

5. An automatic circuit controller comprising a plurality of switches, and electrically controlled compressible resistance means for successively controlling said switches. 90

6. An automatic circuit controller comprising a plurality of electromagnetic switches, and electrically controlled compressible resistance means for successively controlling said switches. 95

7. An automatic circuit controller comprising a plurality of electromagnetic switches, and a plurality of electrically controlled compressible resistance devices for successively controlling said switches. 100

8. An automatic circuit controller comprising a plurality of electromagnetic switches, and electrically controlled compressible resistance devices in series with the magnet coils of said switches for successively controlling the switches. 105

9. An automatic circuit controller comprising a plurality of electromagnetic switches each having an operating coil, and compressible resistance devices in circuit with the operating coils for successively controlling said switches, said devices including actuating elements in parallel with the resistances for controlling the pressure on said resistances. 110

10. An automatic circuit controller comprising a plurality of electromagnetic switches each having an operating coil, and compressible resistance devices in series with the operating coils for successively controlling said switches, said devices including actuating elements in parallel with the resistances for controlling the pressure on said resistances. 115

11. An automatic circuit controller comprising a plurality of electromagnetic switches each having an operating coil, and electrically controlled compressible resist- 120

ance devices in series with said operating coil for effecting the operation of said switches.

12. An automatic circuit controller comprising a plurality of switches, and compressible resistance means controlled by one of said switches for effecting the operation of another, said means including the resistance in one circuit and an electrical actuator in a branch circuit.

13. An automatic circuit controller comprising a plurality of switches each having an operating coil, and a compressible resistance device in series with the operating coil of one of said switches for controlling said switch, said device including an electrical actuator in parallel with the resistance.

14. An automatic circuit controller, comprising a plurality of switches each having an operating coil, and a compressible resistance device in series with the operating coil of one of said switches and controlled by another for effecting the operation of the former, said device including an electrical actuator in parallel with the resistance.

15. An automatic circuit controller comprising a plurality of switches, electromagnetic devices for actuating said switches, compressible resistance means in circuit with said actuating devices and for successively

controlling the actuating devices, and means controlled by the last of the series of switches for deenergizing others of the series.

35

16. An automatic circuit controller comprising a plurality of switches, electromagnetic devices for actuating said switches, a compressible resistance device in series with each of said devices comprising a resistance member, means controlling the pressure on said resistance members for increasing the current passing therethrough, one of said switches controlling the compressible device of the next succeeding switch.

45

17. The combination with an electric motor, of a plurality of resistances in circuit therewith, switches for successively short-circuiting said resistances, compressible resistance means controlled by one of said switches for effecting the operation of the next succeeding switch, and means whereby the operation of the last of the series of switches deenergizes the intermediate switches.
